UNITED STATES PATENT OFFICE.

FRANK L. COGILL, OF BRIDGEPORT, CONNECTICUT.

DESIGN FOR A POST FOR A LAMP, FIRE-ALARM BOX, AND POLICE ALARM-BOX.

49,255.

Specification for Design.

Patented June 27, 1916.

Application filed May 8, 1916. Serial No. 96,242. Term of patent 14 years.

To all whom it may concern:

Be it known that I, FRANK L. COGILL, a citizen of the United States, residing at Bridgeport, in the county of Fairfield and State of Connecticut, have invented a new, original, and ornamental Design for a Post for a Lamp, Fire-Alarm Box, and Police Alarm-Box, of which the following is a specification, reference being had to the accompanying drawings, forming part hereof, and in which—

Figure 1 is a front elevation of the post showing the light signal extension partially broken away. Fig. 2 is a side elevation of the post showing the light signal extension partially broken away and the supporting or anchor members partially broken away.

I claim:—

The ornamental design for a post for a lamp, fire alarm box and police alarm box, substantially as shown.

In testimony whereof I affix my signature in presence of two witnesses.

FRANK L. COGILL.
